UNITED STATES PATENT OFFICE.

JOHN GUNNING, OF BOURNEMOUTH, ENGLAND.

TIME GAS-VALVE-CONTROLLING MECHANISM.

No. 829,269.

Specification of Letters Patent.

Patented Aug. 21, 1906.

Application filed June 2, 1904. Serial No. 210,784.

To all whom it may concern:

Be it known that I, JOHN GUNNING, a subject of the King of Great Britain and Ireland, residing at 100 Holdenhurst road, Bournemouth, in the county of Hants, England, have invented certain new and useful Improvements in Mechanism for Opening and Closing Taps or the Like at Predetermined Times, (for which I have applied for a patent 10 in Great Britain, dated the 28th day of April, 1904, No. 9,764,) of which the following is a specification.

This invention relates to mechanism by means of which a definite movement can be 15 automatically communicated to a movable piece of apparatus at predetermined times—as, for example, the movement required to open and close gas or water taps or electric switches or the like.

It is not usually possible to operate heavy 20 taps or switches by means of the timing mechanism hitherto employed, and it is also frequently advisable, particularly in the case of electric switches, to turn the tap or switch 25 quickly from the closed to the open position and conversely, thereby avoiding in the case cited destructive arcing between the two parts of the switch. This cannot possibly be 30 done when the switch is actuated directly, as has commonly been done, by means of tappets on a slow-moving arbor of a clock.

In the present invention provision is made 35 for operating heavy switches or taps and also for the instantaneous movement of switches or taps from one position to the other, and for this purpose a driving-motor, preferably a coiled spring, is interposed between the timing mechanism and the switch or tap and is connected with the latter in such a manner 40 that while the switch is compelled to move with the motor in one direction it does not turn with it in the opposite direction. The motor is released at predetermined times by means of tappets on the timing mechanism 45 and the extent of its movement at each release limited by means of stops to the extent necessary to produce the required movement of the switch or tap.

The invention further consists in the particular devices by which these objects are effected, as will be hereinafter described, reference being had to the accompanying drawings, of which—

Figure 1 is a front elevation, and Fig. 2 a plan, 55 showing the application of the mechanism to the case of an electric switch which can be suc-

cessively opened and closed by successive rotations of ninety degrees in the same direction. Fig. 3 is a similar view to Fig. 1, but partly in section and showing one of the releasing-levers tripped and the switch in the closed position. Fig. 4 is an end elevation looking at the right end of Fig. 3 turned through ninety degrees. Fig. 5 is a transverse section; and Fig. 6 a partial longitudinal 60 section through the motor-spindle, showing the ratchet-and-pawl driving connection.

The tappets *a b* and the timing-dial *c* are loosely mounted on the main arbor *d* of a clock *d'* and are arranged to be clamped in 70 any required angular positions with respect to each other and to a driving-disk *e*, fixed on the main arbor. In the respective paths of the tappets *a b* are a pair of levers *f g*, independently pivoted on the frame *h* of the apparatus and normally urged by the springs *f' g'*, respectively, to bear on a boss fixed on the motor-spindle *i*. These levers are respectively provided with safety-catches *k l*, which are normally urged, by means of springs *k' l'*, 80 to engage over the catch-bar *m*.

The motor is preferably a simple clock-spring *n* of size sufficient to do the work required of it, which is set by winding it on the spindle *i*. On the spindle-boss are two pairs 85 of stops, one pair of which, *o o'*, are arranged to encounter the end of lever *f*, while the other pair *p p'* are arranged to encounter the end of lever *g*, the two pairs of stops being respectively placed at the ends of a pair of orthogonal diameters.

The spindle *i* is connected, through the ratchet *q* and pawl *q'*, with a disk *r*, from which depend a pair of rods *s*, connected at their lower ends by a bar *s'*, to which is secured in any suitable manner, but so as to be in alinement with the spindle *i*, the spindle *t* of a rotary switch consisting of a switch-arm *t'*, which by being moved through ninety degrees can be brought into or out of contact 95 with the contact-pieces *u u'*, so as respectively to close or open the circuit with which the contacts are connected. The spindle of the switch is connected with the bar *s'* in such angular position that the switch is in the 105 closed position when the end of lever *f* is abutting on either of the stops *o o'*, and consequently when the lever *g* is in engagement with either of the stops *p p'* the switch will be open. The disk *r* has four notches *r'*, which 110 correspond to the four arrested positions of the motor-spindle and switch and with which

a spring-urged dog or detent r^2 engages to prevent rotation of the disk and its attachments in the reverse direction when the spindle i is turned to wind the spring n .

- 5 The tappets and timing-dial are preferably secured to the driving-disk e in the following manner. Pins $a' b'$, secured, preferably, by screwing in the tappets $a b$, respectively, project through annular slots $c' c^2$ in the timing-dial c , struck from the center of the arbor, and are provided with collars $a^2 b^2$, which engage over the edges of the slots. A set-pin e' , which is screwed into the dial c and against the driving-disk e , by separating the dial from the disk and forcing it against the collars $a^2 b^2$ of the tappets thereby frictionally secures the tappets and dial to the driving-disk in any position in which they may be set.
- 10 When the apparatus is in the condition shown in Fig. 1 and the tappets are moved by the clockwork in the direction of the arrow, the tappet b will first encounter the safety-catch l and free it from the catch-bar m , thus unlocking the lever g , which is then displaced by the tappet, so as to withdraw its end from engagement with the stop p and allow the spindle i to be instantaneously rotated by the spring n until the stop o encounters the end of the lever f —that is, it is rotated through a quarter-turn and the switch arrested in the closed position. Further movement of the tappet b clears the tails of the lever g and its safety-catch l and allows them to be returned to their normal positions by means of their respective return-springs. The lever f is prevented from jumping or yielding to the shock of the impact of the stop o from the fact that it is locked by means 40 of its safety-catch, and it remains so locked until its safety-catch has in turn been displaced by the tappet a . Fig. 3 shows the lever g tripped by the tappet b and the switch arrested in the closed position.
- 45 In the apparatus as herein described the levers and their safety-catches are urged to their normal or locking positions by means of springs; but obviously the springs may be dispensed with in cases in which the apparatus can be fixed permanently in such a position that the levers and catches, preferably weighted for the purpose, may be normally held in their locking positions by gravity, and similarly other mechanical modifications 50 may be introduced into the apparatus without departing from the present invention.

Having thus described the nature of my

said invention and the best means I know of carrying the same into practical effect, I claim—

60

1. Apparatus for communicating angular movement to a movable piece at predetermined times comprising a driving-motor, a ratchet-and-pawl connection between the movable piece and the driving-motor, a pair of pivoted levers alternately acting as detents to lock the driving-motor, and means for successively tripping said detents at predetermined times to release the driving-motor; substantially as described.

70

2. Apparatus for communicating angular movement to a movable piece at predetermined times comprising a driving-motor, a ratchet-and-pawl connection between the movable piece and the said motor, a pair of pivoted levers alternately acting as detents to lock the driving-motor, means for successively tripping said detents at predetermined times to release the driving-motor, and safety-catches adapted to maintain said detents in operative position; substantially as described.

75

3. In mechanism for opening and closing electric switches at predetermined times in which the timing mechanism and the opening and closing mechanism are actuated by independent motors, a pair of pivoted levers arranged to act alternately as stops to arrest the switch at the open and closed positions respectively, means for successively tripping said levers at predetermined times to release the switch-actuating mechanism, and safety-catches adapted to prevent the said levers from being tripped until the safety-catch has been displaced and to secure the said levers when acting as stops against displacement by shock; substantially as described.

80

4. In timing mechanism for opening and closing electric switches such as herein described, a timing-clockwork, timing-tappets and a timing-dial mounted coaxially with the main arbor of the timing-clockwork and independently adjustable with respect thereto, a driving-disk secured on said arbor, and means for simultaneously clamping said timing dial and tappets to each other and to the driving-disk; substantially as described.

85

In testimony whereof I have signed my name to this specification in the presence of two subscribing witnesses.

JOHN GUNNING.
